ROTARY IMPACT TOOL

John De Mooy, Shaker Heights, Ohio, assignor to
The Cleveland Pneumatic Tool Company, Cleve-
land, Ohio, a corporation of Ohio

Application October 28, 1937, Serial No. 171,468

5 Claims. (Cl. 192—30.5)

This invention relates broadly to rotary motors, but more particularly to fluid actuated reversible rotary motors of the impact type.

One object of this invention is to produce a 5 rotary motor especially fitted for setting or removing nuts, bolts or the like, and constituting a simple assembly which is strong, durable and efficient.

Another object of this invention is to produce 10 a reversible rotary motor including a work-engaging mechanism for imparting continuous rotary motion to the work until the torque of the motor reaches a predetermined resistance, and thereafter for automatically imparting a rapid succession of rotative impacts to the work for setting or removing the work.

Other objects and advantages more or less ancillary to the foregoing and the manner in which the various objects are attained, reside in 15 the specific construction and aggroupment of the elements peculiar to this structure, as will become apparent from a more complete examination of this specification, in the claims of which there are assembled certain specific combinations of parts and specific constructions indicative of the 20 scope and spirit of the invention.

In the drawing:

Fig. 1 is a longitudinal sectional view of a fluid actuated reversible rotary motor embodying the 25 invention.

Fig. 2 is an enlarged cross sectional view taken in a plane indicated by line 2—2 in Fig. 1.

Fig. 3 is a view similar to Fig. 2, but showing parts in a different position.

30 Fig. 4 is an enlarged cross sectional view taken in a plane indicated by line 4—4 in Fig. 1.

Fig. 5 is a perspective view of one of the pawls included in the mechanism.

Referring to the drawing in which like symbols 35 designate corresponding parts throughout the several views, 10 represents the center housing of the motor accommodating a stator 11 having rotatable therein a rotor 12 carrying radially movable blades or vanes 13, which vanes are responsive to the action of the motive fluid admitted into the stator, in the manner hereinafter described, for effecting the rotation of the rotor. The upper end of the rotor 12 is journaled within a ball-bearing 14 adequately mounted within 40 an upper housing 15 having rotatable therein a valve 16 for controlling the direction of rotation of the rotor 12. The outer end of the upper housing 15 is preferably formed with a flange 17 having secured thereto by cap screw 18 a handle 19, which is provided with a motive fluid conveying

passage 20 controlled by a throttle valve 21, which valve is slidably by a trigger 22. Detachably secured within the outer end of the passage 20, there is conduit connection 23, while the inner end of the passage 20 opens into a passage 24 leading to the valve 16, which valve is formed with a plurality of ports 25 for admitting and exhausting motive fluid into and from the stator 11 through passages 26 and 27 and ports 28.

For purpose of illustration, the prime mover 10 unit above described is represented as a fluid actuated vane-type reversible motor wherein the direction of rotation may be controlled through the valve 16, but it is to be understood that any other suitable prime mover may be substituted 15 for the one above described without departing from the scope and spirit of this invention.

Referring now more particularly to the present invention, 29 represents a front housing having laterally extending lugs 30 each apertured to receive a bolt 31 by which the front and center 20 housings are rigidly secured to the upper housing 15.

Mounted within the upper end of the front housing 29 and extending part way into the center housing 10, there is a stationary bearing-plate 32 accommodating a ball-bearing 33 within which is journaled the lower shafted end of the rotor 12, which rotor extends well into the front housing 29 to form a spindle 34, which is also referred 30 to as a prime mover. To simplify the present disclosure, the spindle 34 is shown as an integral part of the rotor 12, but in practice it is preferably an independent part rigidly connected to the 35 rotor by means of keys, splines or the like.

Rotatably mounted within the front housing 29, there is a cup-shaped casing or driven tool-head 35, which is closed at its upper end by a cover 36 bearing on the spindle 34 and having a reduced portion 37 guided within a ball-bearing 40 38. The lower end of the head 35 is reduced to form a shank 39 journaled within a ball-bearing 40 located within the lower end of the housing 29. The shank 39 has a polygonal portion 41 protruding from the housing 29 to receive a 45 socket member 42, detachably mounted thereon against relative rotation and engageable with the work, which work is represented by a bolt 43. Internally, the shank 39 is accurately machined to rotatably receive the extreme lower end 44 of 50 the spindle 34.

Formed on the internal wall of the cup-shaped head 35, there are two diametrically opposed lugs 45 and 46, each having two laterally inclined side walls 47 and 48. Toward the upper end of the 55

head 35, these two lugs are cut away to produce a short cylindrical counterbore 49 within which is rotatably mounted a cross pin 50 extending through the spindle 34 and carried thereby against relative rotation.

Rotatably mounted within the cup-shaped head 35, in spaced relation with the internal wall thereof, there is a driving head 51, which is laterally supported by two ball-bearings 52 and 53 mounted on the spindle 34. The driving head 51 is drivingly connected to the spindle 34 by a resilient connection including a sleeve 54 made of resilient material such as rubber, which sleeve is mounted on the spindle 34 against relative rotation. This sleeve, which is polygonal in cross section, is closely fitted within a corresponding axial bore 55 extending through the head 51, thereby preventing relative rotation between the sleeve and the driving head.

The driving head 51 is accurately machined to pivotally receive the shank 56 of four pawls or hammer-weights 57, 58, 59 and 60. The pawls 57 and 59 are diametrically opposed to each other and are capable of operative engagement with the lugs 45 and 46 of the head 35 during the rotation of the rotor in one direction, while the pawls 58 and 60 are diametrically opposed to each other and capable of operative engagement with the lugs aforesaid during rotation of the rotor 34 in the other direction. Each pawl is constantly urged into engagement with the inner wall of the cup-shaped head 35 by a spring-pressed plunger 61 carried by the driving head 51, and is formed with a lug-engaging-wing 62 extending substantially the full length of the head 51. Each pawl is also provided with a smaller wing 63 disposed at about 180° from the wing 62, and located within the cylindrical counterbore 49 of the casing 35. As shown in Fig. 2, the wings 63 are normally engaging the cross-pin 50 which is carried by the spindle 34.

In the operation of the motor, motive fluid is admitted into the passage 28 through the connection 23, and if the throttle valve 21 is opened by the trigger 22, the motive fluid is admitted to the valve 16 through the passage 24. The valve 16 may be positioned for admitting motive fluid into the stator 11 through either the ports 26 or 27, for causing the rotation of the rotor in one or the other direction. As shown in Fig. 1, the valve 16 is positioned for admitting the motive fluid into the stator 11 through the passage 26 and the ports 28 for effecting the rotation of the rotor in a counterclockwise direction in Fig. 2, which rotation is of course transmitted to the spindle 34, and therefrom to the driving head 51 through the resilient connection including the sleeve 54. In this instance, the pawls 57 and 59, forced into operative engagement with the side walls 47 of the lugs 45 and 46, will transmit rotation to the head 35, which rotation is transmitted to the bolt 43 by the socket member 42. If the bolt 43 is formed with a left hand thread, this constant rotation transmitted to the bolt 43 will last until the bolt is initially set, or until it reaches a predetermined resistance to rotation which will resist further rotation of the head 35. When this takes place, the spindle 34 driven by the rotor 12 will rotate relative to the head 51 by deforming the resilient sleeve 54, causing the cross pin 50 carried by the spindle 34 and engaging the wing 63 of the pawls to rotate relative to the pawls by exerting pressure on the wing 63 of the pawls 57 and 59 for causing the pivotal or lateral movement of the pawls out of en-

gagement with the side walls 47 of the lugs 45 and 46 of the driven head 35. It will be understood that due to the system of levers including the pin 50 and the pawls 56, a very small movement of the spindle 34 relative to the head 51 is needed to cause complete disengagement of the wings 63 of the pawls 56 with the lugs 45 and 46. In other words, through this system of levers, the rate of speed of the disengaging movement of the wings 63 is actually greater than the rate of speed of the movement of the spindle 34 relative to the head 51. Immediately after the disengagement of the pawls, the rotative energy stored within the resilient sleeve 54 during the deflection of this sleeve, will cause the head 51 to momentarily rotate at a greater rate of speed than that of the spindle 34 until the head 35 has again resumed its normal position relative to the spindle, or until the cross pin 50 is again positioned as shown in Fig. 2 relative to the pawls 56 carried by the head 51. The time element required for the cross pin 50 to move from the position shown in Fig. 3 to the position shown in Fig. 2, is calculated to be less than that required for one half revolution of the spindle 34, causing the pawls to assume their extreme outward position as shown in Fig. 2 before reengaging the lugs 45 and 46 of the head 35. As the driving head 51 rotates relative to the head 35, the pawls 57 and 59 will come into sudden engagement with the side wall 47 of the lugs 46 and 45 respectively, for delivering a rotative impact to head 35, which impact is transmitted to the work 43 through the shank 56 and the socket member 42. This sudden reengagement of the pawls with the head 35, will again momentarily prevent the rotation of the driving head 51, causing the deflection of the resilient sleeve 54 and the limited rotation of the spindle 34 and cross pin 50 relative to the head 51, which relative rotation will again cause the cross pin 50 to move the pawls 57 and 59 out of engagement with the lugs 46 and 45 in the manner above described.

During the rotation of the spindle 34 in a counterclockwise direction in Fig. 2, the pawls 58 and 60 will simply ride the lugs 45 and 46 without interference.

When the valve 16 is positioned for admitting motive fluid into the stator 11 for effecting the rotation of the rotor 12 in a clockwise direction in Fig. 2, the pawls 58 and 60 engaging the side walls 48 of the lugs 45 and 46, will transmit the rotation of the rotor to the head 35. When this head is submitted to a predetermined torque resistance, the resilient sleeve 54 will again allow the rotation of the spindle 34 and of the cross pin 50 relative to the head 51, causing the cross pin 50 to exert pressure on the wing 63 of the pawls 58 and 60 for effecting the disengagement of the pawls. Subsequently, the cross pin 50 will again assume the position shown in Fig. 2, allowing the sudden reengagement of the pawls 58 and 60 with the side wall 48 of the lugs 46 and 45 for imparting a rotative impact to the head 35 and consequently to the work 43 in a clockwise direction in Fig. 2.

From the foregoing description, it will be understood that with this improved motor, continuous rotary motion in either direction may be imparted to the work until the motor is subjected to a predetermined resistance to rotation. Thereafter the driving connection or clutch between the motor and the work engaging member or tool head 35, which clutch includes the hammer-

weights or pawls carried by the driving head 51 and the lugs carried by the tool head 35, will be released to enable relative rotation between the driving head 51 and the driven head 35. As previously stated, the release of the driving connection or clutch is effected by the movement of the cross pin 50 relative to the driving head 51. This cross pin does not form a part of the driving connection, and is actually operable by virtue of the limited relative rotation between the prime mover or spindle 34 and the driving head 35, which relative rotation is responsive to a predetermined resistance to rotation of the tool head or driven head 35. It will also be understood that after disengagement, the clutch or driving connection between the two heads 35 and 51 is automatically reengageable due to the constant pressure exerted on the pawls 57 to 60 inclusive by the spring pressed plungers 61.

20 Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

25 I claim:

1. In a tool of the character described, the combination of two rotatable elements held against axial movement, clutch means drivingly connecting said elements capable of release to enable relative rotation between said elements, said clutch means being automatically reengageable after release, a prime mover, a driving connection between said prime mover and one of said elements enabling limited relative motion therebetween under certain conditions of operation, and means operable by virtue of said relative motion for effecting the release of said clutch means.
2. In a tool of the character described, the combination of two rotatable elements, pawls carried by one of said elements movable relative thereto into driving engagement with the other element and capable of disengagement therewith to enable relative rotation between said elements, said pawls being automatically reengageable after disengagement, a prime mover, a driving

connection between said prime mover and one of said elements enabling limited relative motion therebetween under certain conditions of operation, and means operable by virtue of said relative motion for effecting the disengagement 5 aforesaid.

3. In a tool of the character described, the combination of a driving and a driven rotatable element one within the other, rotation transmitting clutch means between said elements including lugs on said driven element, a pawl carried by said driving element movable relative thereto into driving engagement with said lugs and capable of disengagement therewith to enable relative rotation between said elements, a prime mover, a driving connection between said prime mover and said driving element enabling limited relative rotation therebetween under certain conditions of operation, and means responsive to said relative rotation for effecting the 20 disengagement aforesaid.

4. In a tool of the character described, the combination of a rotatable tool head, a lug extending longitudinally of said head, a rotatable driving member, a pawl pivotally carried by said member capable of lateral movement into and out of engagement with said lug for delivering a succession of rotative impacts to said head, said pawl being automatically reengageable with said lug after disengagement, a prime mover, a 30 driving connection between said prime mover and driving member enabling limited relative rotation therebetween under certain conditions of operation, and means carried by said prime mover responsive to said relative rotation for 35 effecting the lateral movement of said pawl out of engagement with said lug.

5. In a tool of the character described, the combination of two rotatable elements, clutch means drivingly connecting said elements capable of release to enable relative rotation between said elements, said clutch means being automatically reengageable after release, a prime mover, a driving connection between said prime mover and one of said elements enabling relative movement therebetween under certain conditions of operation, and a pin carried by said prime mover engageable with said clutch means by virtue of said relative movement for effecting said release.

JOHN DE MOOY.
